Primary Examiner — T. Chase Nelson(74) *Attorney, Agent, or Firm* — McCormick, Paulding & Huber LLP(57) **CLAIM**

The ornamental design for a sole, substantially as shown and described.

DESCRIPTION

FIG. 1 is a front, top, right-hand side perspective view of a sole comprising a new, original and ornamental design;

FIG. 2 is a front view of a sole comprising the new, original and ornamental design;

FIG. 3 is a left-hand side view of a sole comprising the new, original and ornamental design;

FIG. 4 is a right-hand side view of a sole comprising the new, original and ornamental design;

FIG. 5 is a top view of a sole comprising the new, original and ornamental design; and,

FIG. 6 is a rear view of a sole comprising the new, original and ornamental design.

There is no claim being made to the bottom features, other than those visible in the views of the drawing disclosure, therefore the bottom view has been omitted.
